[57] ABSTRACT

A new biocidal composition for surface and space disinfection comprising, an aldehyde and/or dialdehyde, and a phenol derivative in a solvent. In a preferred embodiment, an anionic surface active agent is added to the composition. The phenol derivative can be substituted or unsubstituted and homologs thereof of phenols, quinolinols and naphthols and their salts used alone or in mixtures. The anionic surface active agent can be from the family of alkyl aryl sulfonates or diphenyl oxide sulfonates. The solvent can be water, benzyl alcohol alkanol or mixtures thereof. Said composition is capable of being sprayed or used in an aerosol composition.

1 Claim, No Drawings

BIOCIDAL SYNERGISTIC COMPOSITIONS FOR SURFACE AND SPACE DISINFECTION

BACKGROUND OF THE INVENTION

1. Field of the Invention

The present invention contemplates novel and unique biocidal compositions for surface and space disinfection which are fast acting, stable, having a long shelf life and capable of acting over a wide temperature and pH range. They are capable of being used as sprays or as aerosols released from pressurized containers. These new biocidal compositions can be used either for surface disinfection of medical, dental or surgical instruments and household objects or for space disinfection as aerosol cleanser-disinfectants.

2. Description of the Prior Art

It has long been known that low concentrations of saturated dialdehydes such as pentanedral in the alkaline pH range (R. E. Pepper et al., U.S. Pat. No. 3,016,328), and in the neutral or acid pH range (G. Sierra, U.S. Pat. No. 3,697,222) display increasing biocidal activity under the influence of various external agents such as heat as shown in G. Sierra, Canadian Pat. No. 865,913, cationic compounds as shown in A. A. Stonehill, U.S. Pat. No. 3,282,775, anionic and non-ionic additives as set forth in R. M. G. Boucher, U.S. Patent application Ser. No. 155,233 or ultrasonics as taught by G. Sierra, Canadian Pat. No. 874,713.

SUMMARY OF THE INVENTION

It is accordingly one object of the present invention to provide a new biocidal composition for surface and space disinfection which is stable having a long shelf life and capable of acting effectively over a wide range of temperatures and pH.

Another object of the present invention is to provide a new biocidal composition which can be used either for surface disinfection of medical, dental and surgical instruments and household objects or for space disinfection as aerosol cleanser-disinfectants.

Yet another object of the present invention is to provide a new synergistic biocidal composition for surface and space disinfection which acts swiftly at room temperature to kill a wide spectrum of microorganisms such as gram positive and gram negative bacteria, vegetative cells, fungii, viroids, viruses and most bacterial spores.

A further object of the present invention is to provide a new disinfectant composition comprising an aldehyde or dialdehyde with phenol derivatives, exhibiting a bioclethal effect when the chemicals are dissolved in either water or alcohol solutions which may or may not contain inert fluorocarbons.

It is also a further object of the present invention to show that specific compatible mixtures in the proper ratio of saturated aldehydes or dialdehydes with phenol derivatives and anionic agents can exhibit a bioclethal effect especially in a pH range equal to or lower than 7, over a wide temperature range (20°C to 100°C), over an extended scale of dilution (50% chemicals concentrate down to 0.03%) when the chemicals are dissolved either in water or in an alcoholic solution which may or may not contain inert fluorocarbons.

A still further object of the present invention is to show that the hereabove described ternary biocidal compositions can also be used in the alkaline range, especially between pH 7 and 9, where they not only im-

prove the lethal effect of the two biocidal components but also extend the shelf life of the solution.

These and other advantages of the present invention will become apparent from the following detailed description and examples.

In accordance with the above objects, it has been discovered that a new strong synergistic biocidal effect is observed when combining the alkylating action of saturated aldehydes and/or dialdehydes on cell proteins with the cell wall physical damage action of phenol derivatives. This action can be further enhanced by adding small quantities of fast penetrating anionic surface active agents.

The dialdehydes or aldehydes which have been found to be effective are those having from 1 to 8 carbon atoms, among which are methanal, ethanedral, propanedral, butanedral, pentanedral, hexanedral, heptanedral and octanedral.

The phenol or phenol derivatives which can be used in the formulation can have one or several phenol functions and can be simple phenol homologs, bis-hydroxyphenyl alkanes, halogenated phenol derivatives, di or tri hydroxyphenols, nitrophenols, amino phenols, quinolins, naphthoquinolins, etc. Derivatives which have proved effective are ortho phenyl phenol, para-nitrophenol, 2 chloro-4 phenyl phenol, o-benzyl p-chlorophenol, p-tertiary amylphenol, 2,5 dinitrophenol, chloro-o-phenylphenol, 8 quinolinol, 8 quinolinol citrate, 8 quinolinol sulfate and o-phenyl phenol sodium salt.

The anionic surface active agents which can be used to enhance the penetration of the formulation are alkyl aryl sulfonates and diphenyl oxide sulfonates.

The solvent is water, benzyl alcohol, alkanol or mixtures of these.

DESCRIPTION OF THE PREFERRED EMBODIMENTS

In accordance with the present invention, there has been found new disinfectant compositions which will kill at room temperature a wide spectrum of microorganisms including gram positive and gram negative bacteria, vegetative cells, fungii, viroids, viruses and most bacterial spores. These compositions exhibit bioclethal effects over a wide pH and temperature range in concentrations of from 0.03% to 50% by weight when dissolved in water and/or alcohol. They are effective in a pH range of from 2 to 10 and a temperature range of from 20°C to 100°C. They are also capable of being mixed with a propellant for incorporation in an aerosol.

As stated above, the composition can be a binary or ternary composition. The binary composition comprises the synergistic effect of the combination of from 0.05% to 3% by weight of the composition including solvent and propellant, if there be propellant present, of an aldehyde or dialdehyde with from 0.005% to 3% by weight of the composition including solvent and propellant, if there be propellant present, of a phenol. The ternary composition adds to the binary composition of from 0.03% to about 2% by weight of the composition including solvent and propellant, if there be propellant present, of an anionic surface active agent. The aldehydes or dialdehydes found to be effective are those having 1 to 8 carbon atoms among which are methanal, ethanedral, propanedral, butanedral, pentanedral, hexanedral, heptanedral and octanedral. The aldehyde most preferred, which will be seen from the following tests is pentanedral (glutaraldehyde).

The phenol and phenol derivatives are phenyl phenol, paranitrophenol, 2 chloro-4 phenyl phenol, O-benzyl p-chlorophenol, p-tertiary amylphenol, 2,5 dinitrophenol, chloro-o-phenylphenol, 8-quinolinol, 8-quinolinol citrate, 8-quinolinol sulfate and o-phenyl phenol sodium salt.

With regard to the ternary composition, the anionic surface active agents which are used to enhance the penetration of the formulation are: alkyl aryl sulfonates and diphenyl oxide sulfonates. Two preferred anionic surface active agents are sodium dodecyl diphenyl ether disulfonate and sodium n-decyl diphenyl ether disulfonate both in liquid form in a concentration of 45%. Some specific examples of these compounds are Dowfax 3B2 registered trademark of Dow Chemical for a sodium salt of a C₁₀ alpha olefin of a diphenyl ether disulfonate and Dowfax 2A1 registered trademark of Dow Chemical for a sodium salt of a dodecylated diphenyl ether disulfonate. Both compounds contain mono and dialkylated species in a ratio of about 80% to 20% mono-to di- and both products are completely sulfonated. These are used in a liquid form having a 45% concentration.

The solvent can be water benzyl alcohol or a low molecular weight alkanol or a combination of one or more of the above. The low molecular weight alkanol can be methyl alcohol, ethyl alcohol, isopropyl alcohol or normal propyl alcohol.

When used as an aerosol, a liquified or compressed gas propellant such as isobutane, propane, freon, chlorofluoroalkanes, ethane, carbon dioxide, nitrous oxide or nitrogen can be used with the above composition.

The solvent or solvent-propellant mixture is present in the composition in an amount of from about 50% to 99.9% by weight of the total weight of the entire composition, including the biocidal solution.

To aid in the understanding of the biocidal synergistic effects of the three different types of chemicals used in the formulation of the present invention, hereinafter are reviewed the main bio-physical and bio-chemical mechanisms which take place at molecular level with each type of chemical used in the novel formulation.

At the moment it is believed that saturated dialdehydes such as ethanedial, propanedial, butanedial or pentanedial produce aldehyde-amino reactions with cell proteins (R. M. G. Boucher et al, Proc. West. Pharm. Soc., Lake Tahoe, January, 1973). The chemical sites for saturated dialdehyde action could therefore involve —NH₂ groups, including cross linking reactions between these groups (D. Hopwood, Histochemistry; 17-151, 1968), although this does not exclude sites of action with other chemical groups (sulphydryl, hydroxyl, carboxy, etc.). It has been well established that aldehydes (and this is particularly true for methanal and pentanedial) have a tendency to form polymers. In the case of pentanedial (A. A. Stonehill et al, Am. Journ. Hosp. Pharm., September, 1963) this chemical loses its biocidal activity when it undergoes polymerization. The rate of polymerization increases with the pH and this limits the use of alkaline pentanedial to two weeks when the solution is buffered between 7.5 and 8.5. Above pH 9 the polymerization is extremely fast and this dialdehyde becomes useless as a biocidal agent.

To avoid aldehydes/dialdehydes polymerization new compositions in the acid range have been recently suggested (R. M. G. Boucher, Am. Journ. Hosp. Pharm., August, 1972). Studies conducted with a 220 MHz pro-

ton Nuclear Magnetic Resonance Spectrometer at the Ontario Research Foundation and in England (P. M. Hardy, et al., chem. Comm. 1969) have shown that in the case of pentanedial the monomer (suspected to be the only biocidal agent) is constantly in equilibrium with various types of polymers. The polymers formed in the acid range are of the acetal-like structure and they can revert to the monomer by heating thus explaining the high biocidal activity disclosed in G. Sierra's patent (U. S. Pat. No. 3,697,222). The polymers formed in the alkaline range are of a different chemical structure and cannot be reverted to the monomer by heating thus explaining the short biocidal life of alkaline glutaraldehyde solutions.

It has also been recently shown (T. J. Munton et al., J. Appl. Bact., 1972) that at room temperature initial uptake of glutaraldehyde by E. Coli cells are the same in the acid and alkaline range. However, under alkaline conditions the outer layers of the cell are damaged to a greater extent. This could explain why at room temperature alkaline glutaraldehyde is more sporidical than acid glutaraldehyde. The reverse being true when the temperature rises. When the external protective layer of a microorganism is difficult to penetrate or to combine with, the biocidal effect of the aldehydes/dialdehydes decreases. This is the case, for instance, of the waxy lipo proteins layer of *M. tuberculosis* which often resists the action of pentanedial. Recent studies by T. Bergan and A. Lystad have shown, for instance, (J. Appl. Bact., 1971) that under Kelsey-Sykes procedure 2% alkaline pentanedial is not tuberculocidal.

To improve the biocidal action of dialdehydes the addition of certain surface active agents (R. M. G. Boucher, U.S. Pat. application Ser. No. 155,233), heat (G. Sierra, U.S. Pat. No. 3,697,222) or ultrasonics (G. Sierra, Can. Pat. No. 874,713) have already been suggested. Combining both phenolic derivatives and aldehydes or dialdehydes with or without anionic detergents is the object of the invention, and we shall show that it provides unsurpassed results for destroying the toughest Mycobacteria at room temperature even when the bacilli are coated with mucous or necrotic caseous substance. This is indeed understandable if one remembers that fast penetration of the aldehyde radicals through cell walls is the key to strong biocidal action. The bactericidal action of phenol depends upon its rendering the cell wall permeable to certain essential cell constituents. This was, for instance, clearly demonstrated by E. F. Gale and E. S. Taylor (J. Gen. Microb., 1947) who found that in the case of *Streptococcus faecalis* a 1% solution of phenol caused a leak of glutamic acid almost as intensive as produced by boiling. That phenol causes leakage of essential metabolites from the cell was also confirmed by measuring the release of radioactivity from E. Coli grown on various labeled compounds (J. Judis, Journ. Pharm. Sci., 1963). The biocidal mechanism of phenol agents is not restricted to cell membrane alteration and as well known, it can also affect bacterial enzymes involved in metabolic phenomena. This has been clearly demonstrated by D. Bach and J. Lambert (J. Am. Pharm. Assoc., 1937). Studies of these authors on certain dehydrogenases of *Staphylococcus aureus* showed that a 1:1000 dilution of phenol acting for 30 minutes destroyed the systems activating succinate, fumarate, pyruvate and glutamate while the lactate, glucose, formate and butanol systems experienced partial inactivation.

The phenol derivatives used in the formula of the invention modify the microorganisms protective membrane to such an extent that they facilitate the penetration of aldehyde/dialdehydes thus promoting a faster killing rate. This has been observed even with hard to penetrate bacterial spores having multilayered coats containing disulphide rich proteins. It has also been observed with the thick cortex layer containing murein in bacterial spores.

To further accelerate the diffusion of aldehyde/dialdehydes into the core of protoplast of microorganisms we successfully added to the aldehyde-dialdehydes/phenol derivative composition small amounts of synthetic detergents of the anionic type. These agents successfully boosted the lethal effect of our new composition while other non-ionic agents reduced or completely destroyed the antimicrobial action of our phenol formulation. In most of our experiments syn-

It is obvious that other substances may be added to the novel compositions of the present invention provided they have no detrimental effects on the biocidal activity of the compositions. Examples of such substances would be perfumes, odor masking chemicals, dyes, pH indicators, anti-corrosion agents, inert fluorocarbons for aerosolization and the like.

Having described the "modus operandi" of the three main classes of chemicals used to observe synergistic biocidal effects, the following examples and tests will further illustrate the invention. They are given primarily for the purpose of illustration and should not be construed as limiting the invention to the details given.

Table I illustrates five typical compositions of the invention which are called A, B, C, D and E. These compositions will later be referred to as (A:100 or B:100, etc.) when used at a 1:100 dilution with water or any other suitable solvent mixture.

TABLE I

thetic cationic agents such as those mentioned in A. A. Stonehill's patent (U. S. Pat. No. 3,282,775) interfered with the phenol additive and destabilized the biocidal composition.

Of special interest were the synthetic anionic detergents of the alkyl aryl sulfonate type, and the diphenyl oxide sulfonates set forth above. These chemicals as shall be shown are stable in the acid pH range and they increase the biocidal activity of the aldehyde-dialdehyde/phenol mixture. Said chemicals at a concentration as low as 0.03% in weight are particularly efficient in the 2 to 5 pH range. They also greatly improve liquid clarity and tolerance of the biocidal mixture to hard water. It has also been found that the above mentioned synthetic detergents do not adversely affect the aldehyde-dialdehydes/polymer equilibrium in the neutral and acid pH range.

To assess the synergistic effect of the Formulation A, for instance, *Mycobacterium tuberculosis* was chosen as a test organism. This choice was made because this microorganism is more resistant to chemical inactivation than other vegetative bacteria. The procedure followed was the official method of the Association of Official Agricultural Chemists published in the JAOAC (4.048-d). Although the official method calls for ten test tubes, thirty were used in all the experiments. Four different culture media were used which are all described in JAOAC (4.045-b, 4048-a, (2) (4) and (5)). Tubes were incubated at 37°C for 60 days then examined for growth. Where results were doubtful, smears were made from the centrifuged sediment, strained by the Z.N. method and examined microscopically for acid fast bacilli.

All these tests reported in Table II were conducted at a temperature of 20°C with a constant exposure time of 10 minutes.

TABLE II

Tests conducted with Composition A (see Table I).
Exposure time: 10 minutes at 20°C.

Culture Media	Chemical Agents													
	P* (2.5%)		An (0.25%)		PL (1.7%)		P+An		P+PL		P+An+PL		PL+An

As previously explained, any increase of temperature will favor the reaction of the pentanedial monomer with cell proteins; and it is also known that Mycobacteria are very sensitive to temperature. It is, therefore, obvious that raises in temperature will only increase the synergistic mycobactericidal effect. This is clearly shown in Table IV.

**Trademark of Dow Chemical Co.

Regarding the influence of pH on the compositions of the present invention, there are two important facts. As previously stated, commercial pentanedial solutions (50 or 25% concentrate) have a pH comprised between 2 and 5. In this range they are already highly bactericidal (this includes pseudomonocidal) due to the presence of a large amount of monomers in equilibrium with reversible monomers. G. Sierra and R. M. G. Boucher (J. Appl. Microb., August, 1971) have shown that the biocidal activity of aqueous acid pentanedial solutions tested with wet naked spores of *B. subtilis* (ATCC 6051) is independent of the pH below 7. It is only in the alkaline range between 7.5 and 8.5 that a surge in biocidal activity (of limited duration in time) is observed before the biocidal action sharply decreases (near pH 9). It is therefore obvious that operating in the acid range will not create a problem with the chosen saturated dialdehydes. Phenols and phenol derivatives are stable in the acid range and generally speaking, the addition of alkali decreases their germicidal action until a point is reached where this action is no longer in evidence (E. J. Ordal et al., J. Bact., 1942). The effect of pH is particularly noticeable when phenols are solubilized with alkyl aryl sulfonates. M. Rosein et al. (Farmacia, 1960) have shown with *S. aureus* a high biocidal activity at pH 3 when using phenols activated with anionic agents. To use an example, 2-4-5 trichlorophenol shows a phenol coefficient of 40 when tested at pH 6 against *S. typhosa* but at pH 10 or higher the phenol coefficient drops to about 1.

This explains why the formulations of the present invention are very effective in the acid range, especially between 2 and 3.8. All the mechanisms involved in the synergistic biocidal effect hereabove described point to a strong microbiocidal action below pH 7. In table V there is shown a series of results obtained with composition A and C which confirm the theoretical considerations.

The tests were of the use dilution type and they were performed according to the procedure described in the AOAC Methods, 11th Edition, 1970. The stainless

steel carriers, free from surface defects, were prepared and sterilized according to the directions. The 48-54 hours cultures of the various bacteria were grown in nutrient broth, prepared as directed in 4.001A with Anatone. These were used to contaminate the cylinders in the manner prescribed. The cultures were examined for resistance to Phenol at 20°C in each case as directed. The resistance to phenol was found to exceed the maximum requirements of the test. As the culture resistance to phenol exceeded the maximum requirements as to concentration and contact time, each culture used was checked to show that it was resistant to phenol in the highest concentration required, and for the maximum time (15 minutes).

The apparatus used for these experiments consisted of an insulated tank equipped with cooling coils and a "Heto" heating and circulating pump. This enabled the temperature to be controlled to $\pm 0.1^\circ\text{C}$. One contaminated carrier was added to 10 cc of composition A at 30 second intervals. Following the contact period the cylinder was subcultured into 10 cc of sterile fluid Thioglycolate media and shaken. The tubes were then incubated at 37°C for 48 hours and examined for growth.

*pH adjusted with buffers

Table V clearly shows that the synergistical biocidal compositions of the present invention are particularly active in the acid pH range. The same family of compounds comprising a saturated dialdehyde, an anionic

agent, and a phenol derivative also exhibits some interesting and unique biocidal characteristics in the alkaline range by a proper choice of chemicals. Composition B shown in Table I is such an example of a formulation with biocidal synergism extended in the alkaline range.

Although conversion of phenol and of the phenol derivatives to the corresponding sodium or potassium phenates causes a reduction in bactericidal power, the phenates are far more soluble than the corresponding phenols. Phenates may also act as solubilizers for the phenols. Thus by increasing the soluble amount of biocidal agents, one compensates for the decreased effectiveness of the phenates. This indeed is well known and explains the wide use of alkaline phenol salt germicidal formulations. One key novelty of the present invention was the discovery that within certain limits of pH (between 7 and 9) mixtures of alkaline phenols do retard the irreversible polymerization of saturated dialdehydes such as pentanedial and ethanedial. In other words, an alkaline pentanedial solution (pH 7 to 9) which normally will start to lose its potency after 2 weeks will retain it after 1 month when mixed with an anionic agent and phenol derivatives. This important observation makes it also possible to prepare highly potent room temperature tuberculocidal formulations with a longer life than those described in U.S. Pat. Nos. 3,016,328 and 3,282,775. It also enables decreasing time for fast mycobactericidal action on highly resistant strains. Table VI and VII provide pertinent data which clearly establishes the biocidal synergism of the compositions of the present invention in the alkaline range.

It is in the acid range (especially between a pH of 2 to 3.8) that the compositions of the instant invention are particularly efficient from the biocidal view point. The choice of the proper phenol derivatives is important in the acid range due to the relatively poor solubility of phenols in water. One of the phenol derivatives which was successfully used in the instant formulations was the para nitro phenol whose solubility in 100 gr of water at 25°C is close to 1.6 gr. Another phenol derivative which gave excellent results is 8-Hydroxyquinoline or 8-Quinolinol which is soluble in aqueous mineral acids. Since the solubility of this chemical is rather poor in non acidified water there was used with great success the 8-Hydroxyquinoline citrate which is freely soluble in water. Also of interest was the 8-Hydroxyquinoline sulfate which is soluble in water but is difficult to use in aerosol formulation due to its relatively poor solubility in alcohol. The 8-Quinolinol derivatives have no toxicity and both the citrate and sulfate do not decrease the biocidal synergism when added to acid so-

lution of pentanedial or other compatible saturated dialdehydes.

lecular shape but also its solubility in the solvent used for the formulation.

It has been established (S. D. Rubbo, et al., *J. Appl. Bact.*, 1967) that the biocidal effect of saturated dialdehydes is related to the presence of two free reactive dialdehyde groups. It is, therefore, obvious that dialdehydes such as propanedial, hexanedial, butanedial, pentanedial, heptanedial, octanedial, etc. can be used to formulate biocidal compositions within the framework of the present invention; however, the biocidal effect is dependent not only upon the dialdehyde mo-

As can be seen in Table VIII, the sporicidal or biocidal activity of the various dialdehydes seem to follow the same general trend as their solubility in water. As a general but not absolute rule, the biocidal activity decreases when the length of the -CH₂- chain increases (i.e. when the distance between the two aldehyde radicals increases). A maximum of biocidal activity is observed with three -CH₂- between the two aldehydes. It is to be noted that according to S. D. Rubbo et al. (*J. Appl. Bact.* 30:1, 78-87, 1967) the presence of two aldehyde groups is a must to observe any biocidal activity. This has been established in a series of tests shown in Table IX comparing the biocidal activity of valeraldehyde (pentanal, CH₃-(CH₂)₃-CHO) with pentanedial (CHO-(CH₂)₃-CHO) in alcoholic solutions. It has also been shown by S. D. Rubbo et al. that substitution in the molecule without alteration of the aldehyde group, as in the methyl derivative of pentanedial, reduces the rate of kill but does not eliminate the biocidal activity. Water base formulation sometimes may not allow increasing the dialdehyde concentration up to the level necessary for fast action. In such cases, the difficulty could be avoided through the use of lower alkanol solvents such as methanol, ethyl alcohol, or isopropyl alcohol.

<i>Staphylococcus aureus</i>	0/30		0/30
<i>Streptococcus pyogenes</i>	0/30		+/30

TABLE IX-continued

Aerosol Germicidal Testing*

	Composition D (See Table I)	Composition D replacing Pantanediol by Valeraldehyde
Trichophyton interdigitale	0/30	+/30

0 denotes no growth in 30 tests

+ denotes growth in 30 tests

*As described in the AOAC, 10th Ed., 1965, p. 89, "Germicidal Spray Products" the spray was applied to the test surfaces by holding the container 8 inches away and spraying for 5 seconds. Lethen broth subculture medium was used with staphylococcus aureus, salmonella choleraesuis and Sabouraud Lethen broth with Trichophyton interdigitale. Trypticase Soy Broth with 10% serum was used with streptococcus pyogenes (beta-hemolytic type A)

To illustrate the importance of the choice of the dialdehyde, S. Rubbo et al. showed that at a pH 8 the time required to inactivate *B. anthracis* by a factor of 10^4 was 15 minutes with pentanediol while little effect was observed with propanediol, all other experimental conditions being equal. In short, from the data presented in Table VIII one can see that the aldehydes to be used in the synergistic formulation are mainly methanal, ethanal, propanediol, butanediol, pentanediol, and hexanediol for aqueous solutions. When formulating alcoholic solutions for aerosol sprays, one could add to the above-mentioned list heptanediol and octanediol.

To further show the effect of the binary composition used as an aerosol, the following tests were made as shown in Table X.

TABLE X

	Aerosol Germicidal Testing*	Composition C (See Table I)	Composition C (without phenol)	Composition C (without aldehyde)
Salmonella choleraesuis	0/30	0/30	+/30	
Staphylococcus aureus	0/30	0/30	0/30	
Streptococcus Pyogenes	0/30	0/30	+/30	
Trichophyton interdigitale	0/30	+/30	+/30	

0 denotes no growth in 30 tests

+ denotes growth in 30 tests

*As described in the AOAC, 10th Ed., 1965, p. 89, "Germicidal Spray Products", the spray was applied to the test surfaces by holding the container 8 inches away and spraying for 5 seconds. Lethen broth subculture medium was used with staphylococcus aureus, salmonella choleraesuis and Sabouraud Lethen broth with Trichophyton interdigitale. Trypticase Soy Broth with 10% serum was used with streptococcus pyogenes (beta-hemolytic type A).

Regarding the phenol or phenol derivatives to be used in the present invention, they can have one or several phenol functions (i.e. free hydroxyl group) and be simple phenol homologs, bis-Hydroxyphenyl alkanes, halogenated phenol derivatives, di or tri hydric phe-

nols, nitrophenols amino phenols, Quinolinols, naphthols, etc. Phenol derivatives choice will be guided, mainly for acid range formulation, by the solubility of these compounds in water or dialdehyde solutions. In some cases it will be advisable to increase the amount of dissolved phenols by adding a certain proportion of alcohols. For the formulations in the alkaline range, it is recommended to use a slight excess in alkali to form the corresponding phenate which acts as solubilizer. The presence of the anionic agents, diphenyl oxide sulfonates or alkyl aryl sulfonates will also help to adjust phenol concentration at the proper level. Compositions F and G, given in Table XI, are two examples of such a formulation for use in alkaline pH range. Table XII shows the biocidal effect produced by the combination of phenol derivatives with pentanediol with and without anionic surfactant in an alkaline formulation.

TABLE XI

	Biocidal synergistic formulas F and G for use in the alkaline range	
	Formula F	Formula G
Vegetable oil soap	10%	10%
Butanediol	1%	2%
Pantanediol	1%	2%
Sodium salt of 2 chloro 4-phenyl phenol (Dowcide 4)	4%	4%
O-phenyl phenol, sodium salt. Tetrahydrate- (Dowcide A)		
Anionic agent (Dowfax 3B2)	5%	5%
pH adjusted between 8 - 10	2%	none

***15 minute exposure to biocidal solution at 20°C (30 test tubes).

Because the biocidal synergistic formulations of the present invention are single phase liquid compositions, they can be used undiluted or diluted (see Table III) on surfaces or sprayed in aerosol form (see composition B and D, Table I). Upon discharge from aerosol pressurized cans, they will produce either coarse wet sprays or fine dry aerosol mists according to the type of valve and according to the physical characteristics of the propellant gas. As previously shown in Tables IX and X, the highly potent biocidal compositions will exhibit a 100% kill both as surface and space aerosol disinfectants. They will also leave a continuous thin film on sprayed surfaces which will remain a sufficient time to disinfect but will not be thick enough to cause spotting.

While not a critical feature of the present invention, best results are achieved when the essential ingredients of the aerosol formulation of the present invention are used in the following approximate proportions by weight:

From 0.05% to about 7% based on the weight of the composition of active material said active material being:

- a. from 20 to 45% of an aldehyde or saturated dialdehydes.
- b. from 15 to 45% of phenol derivatives.
- c. from 5 to 10% of anionic surfactants (when present).

The single phase solvent-propellant mixture may approximately correspond to the following composition by weight:

5

10

20

25

30

- c. water, from 20 to 83% of total weight composition.
- d. alcohol such as methyl alcohol, ethyl alcohol, isopropyl alcohol or benzyl alcohol, from 5 to 70% of total weight composition.
- e. a liquified or compressed gas propellant such as isobutane, propane, Freon, chlorofluoromethane and ethane, carbon dioxide, nitrous oxide, nitrogen, etc. The propellant may appropriately be present in a quantity of about 2 to 25% by weight of the total formulation. As a general rule, well known to the man of the art, the relative amounts of said water, alcohol and propellant in the solvent system are such that said composition has a vapor pressure of from 30 to 70 pounds per square inch gauged at 70°F.

Several typical aerosol formulations which correspond to the teachings of the invention are shown in Table XIII.

A comparison between the two formula in the alkaline range confirms the fact that a saturated dialdehyde with 7 carbons is less biocidal than the 3 or 4 carbons type. In the acid range, one can see that the 8-Quinolinol citrate is more active than a higher concentration of 8-Quinolinol sulfate. One can also see that the ratio of water to alcohol can vary widely without affecting the biocidal activity of our compositions as long as the active agents are completely soluble in the proper amount in the solvent system.

*Dichlorodifluoromethane

**A mixture of about 87% isobutane and 13% propane, by volume, manufactured by Phillips.

It is also important to note that the compositions of the present invention, contrary to pentanedral solutions, are stable over long periods of time even when stored continuously at temperatures as high as 60°C. As can be seen in Table XIV, the compositions of the present invention retain their biocidal activity after high temperature storage both in the acid and alkaline pH range. This is an important feature from the practical view point since in the past it greatly limited all applications with pentanedral solutions. As previously mentioned, the biocidal activity of the formulations described in Stonehill's U.S. Pat. No. 3,282,775, were said to be only 2 weeks when stored at room temperature.

TABLE XIV

Biocidal activity of solutions stored at 60°C.
Microorganism: *Trichophyton Mentagrophytes* ATCC 9533.

AOAC Test Procedure, 11th Ed., 1970

	pH	one month	two months	three months	twelve months
Alkaline glutaraldehyde (2%)	8	+	+	+	+
Composition C with buffer	3.3	—	—	—	—
Composition F	8.5	—	—	—	+
Composition G	8.5	—	—	—	+

Note: tests conducted at 20°C, — no growth, + growth

As has been set forth above and evidenced by the specific examples and tests, novel biocidal synergistic compositions for surface and space disinfection have been produced which are capable of disinfecting at 40

room temperature over a wide pH. The compositions are capable of being used in either a liquid form or as a spray.

Having thus described the compositions of the invention in terms of their preferred embodiments as set forth in the descriptions and examples of the aforesaid specification, it is apparent to those skilled in the art that various changes and modifications can be made in these compositions without departing from the spirit and scope of the invention.

What is claimed is:

1. A disinfectant composition consisting essentially of pentanedral 2.5% by weight, para nitro phenol 1.6% by weight, O-phenyl phenol 0.1% by weight, sodium n-

decyldiphenyl ether disulphonate 0.25% by weight and the remainder water.
